(57) **CLAIM**

The ornamental design for a drainage bag for plant pots and containers, as shown and described.

DESCRIPTION

FIG. 1 is a top plan view of a drainage bag for plant pots and containers showing my new design;

FIG. 2 is a front elevational view of the drainage bag for plant pots and containers; and,

FIG. 3 is a perspective view of the drainage bag for plant pots and containers.

The broken lines showing the container in FIG. 3 are for information purposes only and form no part of the claimed design.
